UNITED STATES PATENT OFFICE.

SCOTT J. MATTHEWS, OF PORT CLINTON, OHIO.

ENGINE LUBRICATOR.

1,420,125.

Specification of Letters Patent. Patented June 20, 1922.

Application filed September 12, 1917. Serial No. 190,906. Renewed November 12, 1921. Serial No. 514,630.

To all whom it may concern:

Be it known that I, SCOTT J. MATTHEWS, a citizen of the United States, and a resident of Port Clinton, in the county of Ottawa

5 and State of Ohio, have invented a certain new and useful Engine Lubricator; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 The invention may be contained in a number of forms of construction and I have selected for purposes of illustration, one form of construction that is illustrated in the drawings and is described hereinafter.

20 Figure 1 of the drawings is a sectional view of the engine taken on the line 1—1 indicated in Fig. 2, and Fig. 2 is a sectional view taken on the line 2—2 indicated in Fig. 1. Fig. 3 is a side view of the lubricator, Fig. 4 is an edge view of the device illustrated in Fig. 3, Fig. 5 is a section of the crank of the engine.

1, Fig. 1 is the engine having a large cooling jacket 2 forming a large cooling chamber 3 that surrounds the engine cylinder 4 and the extended cylinders 5 that receive the valve cages 6. In the wall of the jacket 2 is formed a large recess 7 in which is located the spark plug 8. The jacket 2 is provided 35 with another large recess 9 into which the exhaust pipe 10 may be inserted and threaded into the exhaust passage-way 11 that communicates with the engine cylinder when the exhaust valve is open. The recess 9 and 40 the exhaust pipe 10 forms a large annular chamber 12 that is located within the jacket 2. The exhaust pipe 10 communicating with the short exhaust passageway 11 greatly reduces the amount of heat that would be 45 transmitted to the cooling medium if the passage-way 11 extended its whole length through the chamber 3, as does the passage-way 13 that connects the cylinder with the carburetor 14. The inlet passage-way 13, being surrounded by the chamber 3 and separated therefrom by the cylindrical wall 15, permits the fuel vapor to be heated by the water contained in the chamber 3 to insure 50 ignition and perfect combustion within the cylinder 4 of the engine.

To the upper end of the pipe 16 is connect-

ed and secured the cooling means 17 which consists of a drum 18 for containing a surplus of cooled water that passes down through the pipe 16 into the chamber 3. The 60 upper end of the pipe 16 is secured in the bottom wall 22 of the drum 18 by means of the clamping nuts 23 that thread upon the pipe 16. A second pipe 19 communicates with the chamber 3 and receives the steam 65 and hot water that is formed and heated in the chamber 3 by the combustion of the fuel gases in the cylinder 4.

By the cooling means thus provided the cylinder, the piston, the valve cages and 70 valves are kept at a low temperature and overheating thereof is prevented.

The valve cages 6 are inserted in extended cylinders 5 that pass through the chamber 3 from the valve gear recess formed in the 75 upper end of the engine. The valve cages 6 are cylindrical members that fit into the cylinders 5. The valve heads 33 fit and seat upon the lower ends of the cages 6 in which are formed recesses 11 and 34 that communicate in the one case with the inlet passage-way 13 and in the other case with the exhaust pipe 10. The recess 11 communicates directly with the exhaust pipe 10 that is secured in the wall of the engine and does not pass through the 85 chamber 3 but which is separated from the jacket 2 by means of the annular space 12, while the recess 34 communicates with the passage-way 13 that passes through the chamber 3 and is separated therefrom only 90 by the wall 15. The cylinders 5 and the cages 6 are provided with shoulders 35 that are separated by copper packing rings 36 and the upper ends of the cages are provided with flanges that are 95 separated from the bottom of the valve gear recess by means of the copper packing rings 38. The rings 36 and 38 prevent the escape of the gases, particularly at the time of compression and explosion, by the cages 100 6. The cages 6 are provided with extended cylindrical nipples 39 forming annular chambers within the cages 6 in which are located springs 40 that press against washers 41, located on the upper ends of the valve stems 42 and which are held between the springs 40 and the pins 43. The springs 40 operate to pull the valve heads 33 against end seats formed on the lower ends of the cages 6 in the manner well known in the art.

110 The valve lever frame 46 is provided with downwardly extending lugs 47 that are

placed so as to rest upon the flanges of the cages in the cylinders 5, when the frame 46 is secured by the bolts 48 that are secured in the bottom of the valve gearing recess 5 formed in the top of the engine.

The levers extend from over a passage-way 50 to the upper ends of the valve stems 42. The valves and levers being operated by cams located on a shaft in the crank shaft 10 casing from which motion is communicated to the levers by rods 51 located in the passage-way 50, the levers are so positioned that the ends of the levers operated upon are brought in line with the cams and the vertically extending rods while the ends of the levers operating on the stems are so located as to permit the inlet and exhaust passage-ways to extend diametrically through the engine and at right angles to the crank shaft 20 for advantage of position of the carburetor and the exhaust pipes connected to and leading from the engine. The recess 7 in which the spark plug is located terminates between the cages 6 and consequently between 25 the valves of the engine which give advantage of position for the spark plug.

The levers 53 and 54 differ in their respective lengths and the axes of their pivot pins 55 are displaced by a corresponding requisite 30 distance in order that the movements given to the ends of the levers by the rods 51 may be the same to cause the same extent of openings of the valves. The frame 46 is also provided with a threaded boss in which 35 is secured the threaded stud 59 by means of which the cover 60 may be secured in position over the valve gearing recess 61 formed in the upper end of the engine. The cover 60 may be locked in position by means of the 40 thumb nut 62.

The rods 51 that operate the valve levers 53 and 54 extend down to the cams 64 located on a shaft 65 that is displaced from the vertical plane passing through the axis 45 of the crank shaft in order that the levers 53 may be operated by direct vertical movements produced by the cam 64. The rods 51, are for purposes of adjustment, threaded into rods 65 that pass through holes bored in a shelf 67 forming a part of the end plate 68 of the crank casing 69. The lower ends of the rods 65 are provided with feet 70 that rest against the cam 64. Springs 71 are located intermediate the shelf 67 and the feet 50 and operate to press the feet 70 against the surfaces of the cams 64 and prevent any chattering that may be caused intermediate the feet 70 and the cams 64. Rotation of the rods 51 and 65 are prevented by channels 72 formed in the rods 65 and fingers formed on the plate 73 that is bolted to the shelf 67.

To the shaft 65 which is rotated synchronously with the valve operations may be secured the timer 74. The shaft 65 is supported in the end plate 68. It passes

through bosses formed on each side of the plate 68. Motion is communicated to the shaft 65 by means of the gear wheels 76 and 77 which are located on the crank shaft of the engine and on the cam shaft 65 respectively. To communicate this motion, any form of gear wheels may be used, but for purposes of lubrication, I have found it preferable to provide gear wheels having worm teeth of small angularity with respect 70 to the axes of the wheels. The teeth may be located in any angle within certain limitations, but I have found that teeth located at an angle of 23 degrees is possibly preferable to perform the desired lubricating 75 operations. Using angular teeth as well known, also reduces the noise and clatter caused by rotation of the gear wheels and as hereinafter described finds great utility in providing an efficient propelling means 80 for the lubricant used in keeping the engine thoroughly oiled.

The wheels 76 and 77 are so located that as the teeth come together they operate to squeeze or direct the oil that collects in the 85 teeth of the wheel 77 towards the crank 78. In order to collect oil placed in the bottom of the casing 69, the cam shaft 65 is preferably located below the horizontal plane 90 through the crank shaft. The wheel 77 thus passes to near the bottom of the crank shaft casing 69 and dips below the surface of the oil 79 that is placed in the bottom of the casing 69. In the rotation of the wheel 77 the oil collects between the teeth of the 95 wheel and is carried up to the wheel 76 and by reason of the speed of rotation of the crank and cam shafts, the oil is squirted from between the wheels 76 and 77 towards the crank 78. The crank 78 is provided 100 with an opening 80 that passes through the crank bearing portion of the crank shaft. The outer ends 81 of the crank members are rounded and in the rotation of the crank shaft the opening 80 passes opposite the 105 points of contact between the gear wheels 76 and 77. The teeth of the spiral gears 77 and 76 being located at a slight angle to their respective axes, and the following 110 corners of the spiral gears 77 being located in such a position that they will pass close to the open end of the hollow crank pin, the leading corners of both gears 76 and 77 will first engage and squeeze the oil that is gathered by the teeth of the gears 77 when 115 dipped below the surface of the oil in the bottom of the crank shaft casing and force the oil towards the following corners of the teeth of the gear wheels and shoots it from between the gear wheels in a continuous 120 spurt or stream as indicated at 110. The crank pin in the revolution of the crank shaft 87 rotates so that the opening 80 will pass in line with the stream 110 and be filled 125 in greater part with the oil. The following 130

edge of the opening 80 is slightly extended outwardly to form a lip 82 to catch and retain the oil that shoots into the opening 80. As the opening 80 passes the points of contact between the wheels 76 and 77, the opening 80 being thus formed with an extended lip on the following side will receive a full charge from the stream of oil.

The ends of the opening 80 opposite the side on which the gear wheels 76 and 77 are located, may be closed by a suitable plug whereby a great part of the oil may be retained within the opening 80. Holes 83 are bored through the crank bearing or hollow crank pin and the centrifugal action produced on the oil by the rotation of the crank shaft causes the oil to pass out through the opening 83 and thus oil the crank piston rod bearing. The oil escapes from each side of the bearing and by reason of the centrifugal movement it enters the cylinder 4 and oils the piston. The splashing of the oil against the sides of the casing 69 causes it to diffuse itself over the crank shaft bearings which are thereby also oiled. This is also true of the cam shaft bearing, the cams and the cam rod 65.

I have also provided by my invention, a means whereby the parts contained in the crank shaft casing 69 may be easily made and may be easily assembled and disassembled. The piston may be easily removed from the cylinder by merely removing the lower half of the crank shaft piston bearing and as it passes close to the edges of the gear wheels slipping the piston down from the cylinder 4 and guiding the piston rod 85 outward through the opening 86 formed in the casing 69. It may be returned in the same manner. This will permit the operator to clean the piston and will enable him to get into the cylinder for purposes of cleaning. The plate 68 forms a support for the cams, the crank shaft bearing, the cam shaft bearing, the timer and the cam rods 65. The crank shaft 87 may be easily removed by disconnecting the piston rod, the fly wheel 88 and the rods 51 from the rods 65, whereupon the plate 68 may be unbolted and removed together with the parts supported thereby. This will also draw out the crank shaft 87 and the working parts of the engine contained in the crank casing may then be laid on the operator's bench for inspection, repair or replacement.

By my invention I have also provided crank shaft bearings that may be readily manipulated to take up any wearing that will occur in the operation of the engine. The bearings supports are cast with the plate 68 and with the casing 69. The upper sides of the bearing supports 90 and 91 are split and a bolt 92 passes through the split portion of the bearing supports.

Around the upper two thirds of the bearing

supports and at the ends thereof, channels 93 are formed in the casting. The channels 93 extend about two thirds of the distance around the bearing support and makes the upper part of the bearing supports flexible so that the upper parts may be brought together by a nut 94 when threaded upon the bolt 92. This permits adjustability of the size of the bearing supports 90 and 91. Babbitt bearings 95 may be inserted in the bearing supports 90 and 91. The Babbitt bearings 95 may also be split in two halves or may be split only in the upper sides thereof. When the bearings 95 wear, to take up looseness between the bearings 95 and the shaft 87, the nuts are screwed down on the bolts 92 which forces the bearings 95 closer to the shaft 87.

Around the outer ends of the bearings and in the casing 69, and plate 68, channels 97 are formed which collect the oil that works out from the bearings. This drains down to the bottom of the casing 69.

By my invention is also provided means for lubricating the valve levers and valve stems. In the operation of the crank shaft, the oil is splashed within the casing 69 by the centrifugal action of the crank shaft and forms a spray of oil. The carburetor 14 is connected with the recess 61 formed in the top of the engine and by the suction that is produced in the operation of the piston of the engine, the pressure in the recess or cavity 61 is reduced, and as the air is permitted to pass through the cracks and spaces formed in and around the ends of the bearings of the crank shaft, a supply of oil will be drawn through the passage-way 50 and into the recess or cavity 61 and in quantities such that will keep the recesses or cavity 61 oiled. By reason of the reduced pressure within the recess or cavity 61, and consequently within the casing 69, no oil will work through the cracks of the engine but will be expended entirely in the lubrication of the engine. By this means the engine may be kept clean from oil that would otherwise work through the joints and crevices of the engine casing.

In order to prevent the mist of oil formed by the operation of the crank shaft from entering the carburetor in too great a quantity, an opening 98 is formed in the plate 60. This will permit an increase of pressure within the cavity or recess 61 but nevertheless the pressure within the cavity will be less than atmospheric. It will also supply fresh air to the carburetor while the mist of oil will settle on the levers 53 and 54, the pins 55 and the stems 42 as the fresh air will pass across the under side of the cover 60 from the opening 98 to and through the nipple 99 that is connected to the pipe 100 that leads to the carburetor 44.

If desired, a float 101 may be located in

the crank shaft casing 69 and connected to a rod 102 which will indicate at all times the level of the oil at the bottom of the crank shaft casing.

5. I claim:

1. In an engine, a crank shaft having a hollow crank pin portion, gear wheels having worm teeth for directing oil at right angles to the faces of the gear wheel and 10 into the crank pin.

2. In an engine, a crank shaft having a hollow crank pin portion, gear wheels having worm teeth for directing oil into the crank pin, one of the gear wheels keyed to 15 the crankshaft, the crank pin having openings for communicating with the exterior of the crank pin.

3. In an engine, the crank shaft having a hollow crank pin, the crank pin having an

extended lip on one side of the opening, a 20 pair of worm gear wheels for directing a stream of oil into the hollow crank pin.

4. In an engine, a plurality of moving parts, a pair of worm gear wheels meshing in proximity to the parts, the worm gear wheels having teeth located at an angle to the axes of rotation, the axes of rotation located in parallel relation and the following corners of the teeth of the spiral gears located in proximity to and on that side of the spiral gears on which the said moving parts are located, a container for oil, one of the gear wheels dipping below the surface of the oil whereby a continuous stream of oil will be thrown upon the parts. 30

In testimony whereof, I have hereunto signed my name to this specification.

SCOTT J. MATTHEWS.
